UNITED STATES PATENT OFFICE

EDWIN V. SWANGREN, OF MAYWOOD, ILLINOIS, ASSIGNOR OF ONE-HALF TO WALTER N. STEVENSON, OF EVANSTON, ILLINOIS

CAP-LINING MACHINE

Application filed September 1, 1928. Serial No. 303,586.

My invention relates to a machine which is designed for the rapid commercial production of finished paper-lined caps or tops such as are used as closures for various kinds of jars and bottles, and operates upon strips of paper supplied to the machine to cut out the lining disks, and then apply the disks to the caps or tops which are automatically fed into position to receive them, the lined caps being then discharged from the machine. The object of my invention is to provide a machine which by reason of certain novel features in the construction and arrangement of parts and members which I have devised for the purpose, as hereinafter described and explained, shall operate rapidly and accurately to accomplish the ends in view, and be particularly suitable for continuous hard service. My invention resides in the novel combination of cooperating members and mechanisms which constitutes my cap-lining machine, and certain novel combinations and sub-combinations of mechanical parts and elements relating to the mechanisms for feeding the paper strips from which lining disks are cut, the mechanism for cutting the disks, the mechanisms for introducing the caps into the machine and positioning them into position to receive the liners, the means for assembling the caps and liner disks, the means for discharging the lined caps, and the actuating means by which the various parts of the machine are operated in synchronism. In the appended claims, I have more particularly set forth the essential elements of my invention, it being understood, however, that variations and modifications of construction and arrangement of parts of the machine, as by the substitution of equivalent elements and mechanisms for parts specifically described are possible, without departing from the spirit of my invention, and I therefore intend my claims to be construed to include all equivalent elements within the true scope of my invention.

In the drawings, Figure 1 is an elevation of what for convenience of description will be termed the front end of the machine; Fig. 2 is an elevation of the rear end; Fig. 3 is an elevation of the right side of the machine;

Fig. 4 is an elevation of the left side; Fig. 5 is a plan view of the machine; Fig. 6 is a vertical longitudinal section of the machine in a plane indicated by the dotted line 6-6 on Fig. 1, many of the parts being shown in elevation; Fig. 7 is a horizontal section of the front portion of the machine in a plane indicated by the dotted line 7-7 of Fig. 1; Fig. 8 is a fragmentary longitudinal vertical section of the upper central portion of the machine in a plane passing axially through the die and assembling mechanisms; Fig. 9 is a transverse vertical section in a plane at right angles to the plane of Fig. 8 and also passing axially through said die and assembling mechanisms; Fig. 10 is a fragmentary section in a transverse vertical plane extending axially of the paper feed rollers of the machine; Fig. 11 is a fragmentary view showing the connection of the liner disk plunger rod with the rod by which it is actuated; Fig. 12 is a fragmentary view showing a cam groove and roller connection by which said actuating rod is operated; Fig. 13 is a detail showing in section an extended ball bearing for supporting the inner ends of the rollers which support the delivery belt of the machine; Fig. 14 is a detail top plan view of parts adjacent a turret or star wheel employed to advance the caps, a cap member, or cover, above the wheel being removed; and Fig. 15 is an enlarged detail illustrating a yielding mounting for a star wheel employed as a conveyor member.

Like reference characters indicate like parts in all the figures of the drawings.

First describing briefly and generally the construction of the machine, the caps to which the paper disks are to be applied are supplied by an operative in inverted position to a feed chute from which they pass to a rotating table. This feed table delivers the caps to one end of a feed belt from which they are removed at the other end by an intermittently rotating turret or star wheel which transfers them into the orifices of a cap disk conveyor having a synchronous movement. This disk carries the caps in a circular path over the upper surface of a supporting table to a working point into alignment with and im-

mediately below a die mechanism for cutting out liner disks from a strip, or a plurality of strips, of paper led into its path by suitable intermittently-acting paper feeding mechanism. With this die mechanism is associated a plunger device which forces the liner disks immediately after they are formed into the caps, after which the caps are carried by the cap conveyor over an orifice in the supporting table, through which they pass to a transfer belt which transfers them to an inspection belt where they may be inspected and from which they are delivered to a storage receptacle.

Describing now the specific construction of the machine as illustrated in the drawings, it may first be stated that the principal members of the machine frame are a base plate A, having a lateral extension B on the left side of the machine to provide a motor support and a rearward extension C to support a pedestal upon which the paper reels are mounted; a right side leg casting D formed with front and rear legs connected by plate and flange elements appropriately designed to afford bearings and other supports for the moving and stationary parts of the various mechanisms; a left side leg casting E likewise formed with front and rear legs and providing supports for various parts; a bed plate or table F, and various other bracket members and supporting parts secured to those mentioned which will be referred to later as the description proceeds.

The feed table 1 of the machine, which is a thin disk continuously rotated by actuating connections hereinafter to be described, is mounted in a feed table bracket G secured to the front of the left side leg casting E before mentioned, near the top thereof,—see Figs. 1 and 5. Immediately below the feed table and extending tangentially of its rear side towards the center line of the machine is a feed belt 3, engaging a roller 4 fixed to shaft 5 journaled in the bracket 2 before mentioned and a roller 6 fixed to a short shaft 7 rotatably mounted in a hub 8 formed on a bearing bracket H at the front of the machine. The feed belt runs in a shallow groove formed in a plate 9 which is suitably supported by a pair of cross-strips 9^a and bracket strips 9^b, one pair of bracket strips being secured to the frame bracket G, and the other pair to a post 2 formed on said frame bracket, and is maintained taut by a belt tightener consisting of a tensioned rocking lever 10 carrying an idler roller 11 engaging the belt. A pair of rails 12—12 adjustably secured through slotted L-shaped lugs 12^a to said cross-strips 9^a and also secured to a feed chute member 13 arranged immediately above the feed table serves to guide the train of caps to be lined on their way from the feed table to the succeeding mechanisms. The rails 12—12 are continuous with the side members of the chute and extend concentrically over a portion of the table,

the chute being open at the bottom over the feed table. At its front or feeding end the sides of the chute are connected by a bottom member forming a trough within which the caps can be arranged and manually supplied to the feed table.

The feed belt 3 is arranged to convey the caps upon it to a position at the inner end of the cap guide-way, at which point each one of the line of caps which successively becomes the foremost cap is blocked by a vertically reciprocating stop finger 14 projecting downwardly from the horizontally bent upper portion 14^a of a lift rod 15 mounted to slide vertically in bearings in the framework of the machine. Inasmuch as the feed belt has a continuous movement, the frictional drag of the belt during the period which the foremost cap is blocked by the lowered stop finger extending into it closes up all gaps in the line of caps, and as soon as the stop finger shifts to clear the rear wall of the cap, the latter is shifted forwardly by the belt a short distance, uniform in the case of each cap, onto a turret plate 200 secured to the top of the bearing bracket F before mentioned, and into the path of a turret or star wheel 16 which is connected to a vertical shaft 17 journaled in bearings formed in said bracket, and is arranged to be intermittently rotated as hereinafter described,—see Figs. 5 and 8. The downward movement of the stop finger 14 after the forward cap has moved from beneath it, brings it into similar engagement with the next succeeding cap. The turret plate 200 is notched as indicated at 200^a, Fig. 14, to accommodate the inner loop of the belt, and is cut away or peripherally notched, as shown at 200^b on the side next the center of the machine, so that as the caps are pushed by the star wheel around its axis in the direction indicated by the arrow on Fig. 5, they may drop downwardly from the plate. The caps on the plate are constrained to move in a circular path by the circular wall 19 of a cap member 20 secured to the top of the bearing bracket F, and are shifted in successive steps until they severally arrive at a position of registration with the orifices of an intermittently rotated orificed cap conveyor 21, the upper face of which lies in a plane immediately beneath that of the plate 200. A downwardly inclined arcuate spring 20^a, secured to the cap 20 immediately above and in the path of the caps, is yieldingly cammed upward by the successive caps as they advance towards the peripheral opening in the turret plate, and as the turret wheel comes to rest the spring serves to snap the cap which has come into registration with such opening downwardly into the orifice below it in the cap conveyor.

The cap conveyor, as illustrated, (see Fig. 8) is a flat disk 21 secured to a short hollow vertical shaft 22 journaled in a hub on the

bed plate member F of the machine frame, and is given an intermittent movement, as hereinafter explained. In the present instance, the shaft 22 is formed with a flange 22^a at its top, seating in an annular recess at the top of its bearing in the hub, and above the disk 21 is provided a ring 24 which through screws engaging threaded seats in the flange clamps the disk to the shaft. To 5 the lower end of the shaft 22 are secured a Geneva wheel 201 and a gear wheel 202 meshing with a pinion 203 fixed to the shaft 17 before mentioned, by means of which (through operating connections later to be 10 described) the star wheel 16 and cap conveyor 21 are given a synchronous movement which brings the notches of the turret or star wheel successively into registration with the orifices 25 of the cap conveyor at periods of rest, permitting the caps to drop successively out of 20 the path of the star wheel into the orifices of the conveyor and upon a smooth face formed upon the bed plate member F before mentioned constituting a conveyor table.

25 As illustrated in Figs. 8 and 9, the orifices of the cap conveyor are formed in removable filler plates 21^a in order that by interchange of sets of filler plates formed with openings of different size, the machine may be adapted 30 to operate upon caps of different diameters.

It may here be explained that to avoid accidental injury to the star wheel mechanism which otherwise might occur from a cap jamming in the star wheel should it fail to 35 completely enter a notch thereof from between the rails 12—12 of the feed passage, the shaft 17 is equipped with a flange member 304 formed with a pair of opposite radial ribs 305—305 which are wedge shaped in cross 40 section, and the star wheel is secured to a collar 305^a—305^a which is formed with complementary radial grooves. By means of a spring 306 confined between a nut 307 on the upper end of the shaft 17 and a loose washer 45 bearing on the upper face of the star wheel, (see Fig. 8) the ribs 305 are yieldingly held in the mating grooves of the collar fixed to the star wheel, so that the shaft and star wheel will rotate as one under normal conditions, 50 but under positive resistance due to the jamming of a cap, the star wheel will be cammed upward to permit rotation of the shaft alone and injury thus avoided. It has been found in practice that the jar produced by the 55 snapping of the star wheel upwardly and down again when a jam occurs serves in most cases to dislodge the cap which is jammed, and the regular feeding operation is immediately resumed.

60 After each cap has dropped into its particular orifice in the cap conveyor, it is carried around upon the cap table to a point of rest in its path of travel,—in the present instance, but not necessarily, a diametrically 65 opposite point,—at which point of rest it

comes into alignment with the member of the liner-disk cutting and liner-seating mechanisms.

The fixed die member 25^a of this mechanism is seated in a block 26 removably secured above an interposed spacer plate 26^a to the bed plate member F of the machine frame, see Figs. 5 and 9. It is obvious that by removing the securing screws which hold the block 26 and spacer plate 26^a to the frame (the ring 24 of the cap conveyor being first removed), the associated members, including the lower die member, may be removed to 70 permit interchange of parts. The movable member is a punch 27, the working portion 75 of which is tubular in form, secured to a removable block 28 forming part of the cross-head 29 of a movable frame 30 mounted to have a vertical sliding movement. This movable punch frame includes the cross-head 29, a pair of vertical guide rods 31—31, and a yoke 32 secured to the lower ends of the guide rods,—see Figs. 1, 6 and 9,—and is reciprocated by means later to be described. 80 In the present instance,—see Figs. 6, 8 and 9,—the rods 31 have long bearings in a pair of tubular guide brackets 33 which are bolted to opposite sides of the bed plate F, and are cut away to clear the cap conveyor,—see Fig. 5. To further guide the punch member, the 85 block 26 secured to the bed plate F is equipped with posts 34 and the block 28 secured to the movable frame is formed with sockets engaged by these posts, (see Fig. 9) so that 90 accurate registration and engagement of the punch and die members are assured.

By reciprocation of the punch frame and the tubular punch member carried by it, lining disks are successively cut out from the strips (or single strip) of paper intermittently fed between the punch and die members during an interval of rest in the movement of the cap conveyor, and the severed lining disks are immediately thereafter forced into 100 place into the cap at the time below the die, by means of a liner-seating plunger 35 secured to a vertical stem 36 which is slidably mounted coaxially of the die members in the cross head 29 of the movable frame,—see Figs. 8 and 9. In the present instance, to provide for change of punching members and liner-seating plungers, the stem 36 consists of interlocked upper and lower members, a and b,—see Fig. 11. The front 105 side of the cross-head is formed with an opening opposite the joint in the plunger stem, and it is obvious that by removing the screws which secure the block 28 to the cross head the block and parts associated with it 110 may be removed as a whole. To prevent the plunger from dropping down into the die 25^a during removal, a hole is drilled through the lower portion b of the plunger stem, into 115 which a pin may be temporarily inserted. 120

- Near its top, and opposite a recess in the rear side of the cross-head, the stem 36 is formed with a rack intermeshing with a toothed segment 37 secured to the inner end 5 of a shaft 38 which is journaled in bearings on said cross-head. The outer end of said shaft 38 carries a pinion 39 meshing with a rack plate 40 which is slidingly mounted in a portion of the bearing bracket in which the 10 shaft 38 is journaled, and is yieldingly connected with an actuating rod 41 which slidingly passes through a bore formed in it, by means of a coiled compressing spring 42 interposed between the bottom of the rack 15 plate and a collar 43 secured to the rod below such plate,—see Figs. 1 and 11. The actuating rod 41 is pivoted to the free end of a rocking arm 44 by which it is given a vertical movement through a cam roller 45 20 intermediately pivoted on such arm and arranged to engage a cam groove 46 formed in the side face of a gearing member later to be described,—see Fig. 12.
- Inasmuch as more or less loose motion in 25 the connection for reciprocating the liner-seating plunger will inevitably develop in use, and the downward throw of the plunger would tend to batter the cap below the plunger unless prevented, I have provided a buffer which can be quickly and accurately adjusted to prevent this injurious effect. This buffer consists of a leather washer 36^a near the top of the upper section *a* of the plunger stem, backed by an adjusting nut 36^b on said 30 stem, the leather member being arranged to bring up against a stop surface on the top of the cross head 29 and sustain the downward stroke of the plunger at the exact point necessary to avoid injury to the cap.
- In order to accommodate the machine for work upon caps having domed heads, or heads having an easily marred portion, I have provided below the die elements a removable filler plate 150 which is interchangeable with filler plates having any desired contour adapting them for use with the particular caps to be operated upon.
- The intermittent rotary movement of the cap conveyor shifts the caps successively into 50 a position of registration at a subsequent interval of rest with a discharge opening or gap 151 in the conveyor table, through which the caps may fall, one by one, onto the upper reach of continuously moving endless belt conveyor or transfer belt 47.—see Figs. 3, 5 and 6.
- Inasmuch as the orifices of the cap conveyor must be but slightly larger in diameter than the caps in order to ensure correct alignment under the die and plunger mechanisms it is desirable to provide an ejector mechanism for positively forcing such cap downwardly from its orifice through the opening in the conveyor table, in case it should fail to fall therethrough by gravity.
- This ejector consists of a plunger head 210

on the lower end of a rod 210^a which is carried by parallel arms 211—212 which are pivoted to the punch frame 30, see Fig. 3. A portion of the arm 211 extending rearwardly of its pivot is connected by a link 211^a with 70 the machine frame, so that the vertical movement of the punch frame imparts a multiplied movement to the plunger,—see Figs. 3 and 6.

The transfer belt 47 above mentioned is 75 mounted upon a driving roller 48 secured to a longitudinally extending shaft 49 through which it is driven and an idler roller 50 journaled in bearings carried by a stationarily supported frame plate 51,—see Figs. 1, 2, 6, 80 and 7. As the caps are carried on the face of the belt towards the right of the machine they are cammed rearwardly by a stationarily supported guide finger 52 and drop onto the upper reach of a broad inspection belt 53 which has a slow intermittent movement and from which the caps pass to any convenient receptacle. The relatively slow intermittent movement of the inspection belt, in connection with action of the guide finger 85 on the continuously moving single line of caps on the more rapidly moving transfer belt, acts to crowd successive caps laterally off the transfer belt in a somewhat irregular manner, spreading out widely over the surface of the inspection belt, so that adequate opportunity for inspection and removal of defectively lined caps is thereby afforded. In case of a stoppage in the feeding of caps through the machine, while the die mechanism is cutting out liner disks which pass on to the transfer belt, the paper liners pass under the guide finger and are not delivered to the inspection belt.

The inspection belt 53 is mounted upon a rear driving roller 54 fixed to a shaft 55 which is journaled at its inner end in a bearing carried by the right frame member D and at its outer end in a bearing carried by a frame bracket 56, and upon a front idler roller which is carried by a long stud 57 secured to the free end of a swinging adjusting arm 58 angularly adjustable upon a clamping bolt 59 by which it may be rigidly secured to the frame. The frame plate 51 above mentioned is secured at one end to the stud 57 and at the other to the frame bracket 56.

The mechanism for feeding paper to the liner disk cutting members may now be described. In the present instance two disks 110 of paper are intended to be placed simultaneously in each cap, and consequently means for simultaneously feeding two strips of paper are employed. The upper paper reel 60 and lower paper reel 61 are both pivotally mounted in a pedestal 62 bolted to the extension C of the base plate before mentioned,—see Fig. 4.

Inasmuch as a smooth running and substantial support for the paper reels is im-

portant, and it is also important that means be provided for quickly removing an empty reel and substituting a fresh one, I have devised for the purpose the particular form of 5 assembled bearing unit shown in section in Fig. 13, in which the hub member 63 of the reel is equipped with a pair of internal spaced bearing rings 64—64^a formed with ball races, and a bearing stud 65 is provided which is de- 10 tachably secured to a socket in the pedestal by means of a set screw 66. The bearing ring 64^a is of larger diameter than the ring 64 and is seated in an annular shouldered seat at the outer end of the hub.—to the right in 15 Fig. 13. The stud 65 is shouldered, to provide a seat on its central portion 65^a for a bearing ring 67 formed with a ball race to receive balls by which it is rotatably connected with the ring 64^a, and the portion 65^a is 20 shouldered to provide a seat on the reduced end portion 65^b for a bearing ring 68 formed with a ball race to receive balls by which it is connected with the ring 64. The ring 67 is held in place on the stud by a collar 69, 25 and the ring 68 by a washer 68^a and nut 68^b on the end of the stud. The assembled bearing members together with the bearing stud 65 are retained in assembled relation by means of a ring 70 secured to the inner end 30 of the hub. It is obvious that by loosening the set screw 66 the assembled bearing unit and the reel of which it forms a part can be removed as an entirety to permit a change of reels.

35 From the upper reel the paper runs over an idler roller 71, and from the lower reel over an idler roller 72, both of which are rotatably mounted in a vertical bar 73 which is secured to a pair of supporting rods 74—74^a, 40 secured to the pedestal 62,—see Figs. 3, 4, and 5.

From the rollers 71 and 72 the strips of paper run together between a pair of guide rolls 75—75^a, then over a guide roll 76, under 45 a guide roll 77, over a guide roll 78 and under a guide roll 79, all of which are rotatably mounted in a tension frame consisting of a pair of horizontal guide plates 80—81 arranged to be simultaneously adjusted to- 50 wards and away from the center line of the strips of paper. To this end the plates 80—81 are equipped with oppositely screw-threaded blocks 80^a making engagement with opposite right and left screw-threaded sections of a 55 pair of supporting bolts 82—82 which are rotatably mounted in opposite ends of a bracket 83 (see Figs. 4 and 5), the bolts being provided with hand wheels 82^a for turning them,—see Fig. 3.

60 Forwardly of the front guide roll 79 the strips of paper pass together between lower and upper feed rolls 84 and 85 respectively, both rolls being positively driven and the upper roll being tensioned and mounted in bearing blocks 86—86 which may be shifted

vertically to release the paper between the rolls. To this end the blocks 86 are slidably mounted in frame brackets 87—87, and are adjustably tensioned by springs 88—88 interposed between such blocks and adjusting 70 screws 88^a—88^b, and are arranged to be simultaneously lifted against the stress of the springs by rearwardly extending arms 89 secured to a rocking frame 90 pivoted in bearings on said bracket,—see Figs. 8 and 10. 75 To rock this frame an eccentric disk 91 secured to a shaft 92 journaled in said frame bracket and arranged to cooperate with a projection 93 on the cross member of said frame is provided, the shaft 92 having secured to it an actuating handle 94 for the purpose.

From the feed rolls the paper strips pass underneath an orificed guide plate 95 to the dies, (see Fig. 8) and the perforated strips then pass from between the dies over a guard plate 96 to the front end of the machine, where it is discharged and may be removed in any desired manner.

Describing now the operating connections 90 whereby the different mechanisms above described are actuated, the shaft of the motor 97, supported by the extension B of the base plate, is provided with a pinion 98 arranged to mesh with a gear wheel 99 fixed to the left 95 side section of a two-part clutch shaft 100, the right and left sections of which are journaled in bearings in the right and left side leg castings, respectively, see Fig. 7. At the right side of the machine the right section of 100 this shaft 100 is provided with a hand wheel 101 by which it may be manually turned for the purpose of varying the position of connected parts in making adjustments of cer- 105 tain of them.

The two sections of the shaft 100 are connected by a clutch 102 (see Figs. 2 and 6), the details of which need not be here explained, which is actuated to connect, or disconnect them by means of an intermediately pivoted hand lever 103, a link 104, and a pivoted yoke 105 straddling one of the clutch elements and arranged to shift it into and out of engagement with the other clutch element.

To the right end of the shaft 100 is secured a pinion 106 arranged to mesh with a large gear wheel 107 fixed to a shaft 108 which is the main power shaft of the machine and is journaled in bearings in the right and left side castings of the machine frame, the lower part of each bearing being formed in a downwardly bowed frame member 109 (see Fig. 1) which is bolted to the right and left side leg members.

Near the center of the machine the shaft 108 carries an eccentric 110 which is connected by a strap and pitman 111 with the yoke 32 of the punch frame, whereby the latter is reciprocated, the ejector rod 210 being actu-

ated by the frame in the manner before described,—see Figs. 1 and 6.

The shaft 108 also carries a pinion 122^a arranged to mesh with a pinion 113 fixed to a shaft 114 which is journaled in bearings in the side members of the machine frame,—see Figs. 1 and 6. To the face of the pinion 113 is secured a bevel pinion 115 arranged to mesh with a bevel pinion 116 fixed to the lower end of a vertical shaft 117 journaled in bearings formed in a frame bracket 118 bolted to the left side frame member of the machine frame. Secured to the upper end of this vertical shaft 117 is a crank arm equipped with a roller 119 and multilated locking disk 120 arranged to cooperate respectively with radial notches 120^a and arcuate faces 120^b in the Geneva wheel 201 hereinbefore mentioned, and which is secured to the shaft 22 carrying the cap conveyor,—see Fig. 7. Through the gear wheels 202 and 203 the intermittent movement thus given the cap conveyor is also imparted to the star wheel 16 so that these two members have the synchronous movement already described.

The cam groove 46 which is arranged to actuate the cam roller 45 for the purpose of actuating the liner plunger 35 mounted in the main frame in a manner already explained, is formed on the inner face of the gear wheel 107.

To the left end of the shaft 114 above mentioned is secured a pear-shaped cam 121 (see Fig. 4) arranged to cooperate with one end of a rocking lever 122 journaled in the left side frame member, the other end being arranged to operate the lift rod 15 before mentioned to lift the contact finger 14 at proper intervals.

Upon the left end of the shaft 108 is secured a crank plate 123 equipped with a wrist pin mounted on a radially adjustable block 123^a to vary the length of stroke of a pitman rod 124 pivoted on such pin. The pitman is pivoted to a rocking arm 125 carrying the housing and ring member 126 of what is commercially termed a "Horton friction ratchet" (see Figs. 4 and 10), which includes a ratchet wheel formed with wedge faces and the ring when the members are rotated relatively in one direction and run free when rotated in the opposite direction. The ratchet member 127 of this one-way clutch, or ratchet, mechanism is fixed to a gear wheel 128, the hubs of both the attached gear wheel and ratchet, and the housing member, being rotatably mounted on a stud 129 rigidly mounted in the frame of the machine.

The gear wheel 128 is arranged to mesh with a pinion 129^a secured to a shaft 130, which is journaled at one end in the frame bracket 87 before mentioned and extends across to the right side of the machine. The lower feed roll 84, is fixed to the shaft 130, and this shaft also carries a pinion 131 arranged to mesh with a pinion 132 fixed to the

shaft 133 which carries the upper feed roller 85,—see Fig. 10.

Inasmuch as the moving parts of the intermittent paper feed mechanism have considerable momentum, I have provided a brake mechanism to steady their movement. This mechanism includes a friction drum 134 engaged by opposite arcuate faces formed on a pair of spring-tensioned brake jaws 135—135 which are pivoted together at their rear ends, and at their front ends are orificed to engage a stationary retaining or supporting bolt 136 secured to the bed plate of the machine,—see Figs. 5, 6, and 10.

At the right side of the machine the shaft 130 carries a pinion 137 which is arranged to mesh with a relatively large gear wheel 138 fixed to the shaft 55 upon which the driving roller of the inspection belt 53 is mounted,—see Figs. 2, 3, and 7.

The feed belt 3 and feed table 1, and also the transfer belt 47 are continuously rotated by the following train of connections. The left hand section of the clutch shaft 100 carries a driving pulley 139 engaged by a belt 140 (see Figs. 2 and 3) which drives a pulley 141 fixed to a shaft 142 journaled in bearings formed in the opposite side members of the machine and equipped with a worm 143 (see Figs. 2 and 3.) The worm 143 is arranged to mesh with a spirally toothed pinion 144 secured to the shaft 49 before mentioned, which is journaled in a front bearing formed in the bearing bracket H and a rear bearing formed in the bed plate F of the machine, and has secured to it the driving roller 48 engaged by the transfer belt (see Fig. 6).

To the front end of the shaft 49 is secured a sprocket wheel 145 engaged by a sprocket chain 146 which engages a sprocket wheel 147 fixed to the short shaft 7 before mentioned, which is journaled in the bearing bracket H and to which is secured the roller 6 through which the feed belt is actuated (see Figs. 1, 5, 6, and 7).

The shaft 5 which carries the roller 4 and is rotatably mounted in bearings formed in the feed table bracket G near its front end is also equipped with a bevel pinion 149 rotatably mounted on a vertical bearing stud carried by the front end of the bracket G and to the upper face of this pinion is secured the feed table 1.

The direct connection to the motor of the feed table and feed belt for advancing caps to the mechanisms which are connected to the motor by the clutch 102 enables caps to be brought up to the star wheel before the paper-punching mechanism begins to operate, and should gaps occur in the line of caps advancing to the star wheel, the mechanism connected through the clutch may be temporarily disconnected until the gaps are closed up.

It will be understood that while the ma-

chine illustrated and above particularly described is adapted to apply to two liner disks usually employed, the lower one formed of a relatively thick material and the upper one a thin close-grained material, both paraffined in advance, it is possible, by the provision of additional paper reels and guide rolls, to apply additional liner disks to the caps, three, or four, liner disks being sometimes employed. It is obvious that it is further possible to incorporate coating mechanism for paraffining the paper intermediate the paper rolls and the punching mechanism of the machine.

Claims:

1. In a cap-lining machine, a stationary conveyor table arranged to support the caps, an intermittently rotated cap-conveyor above and adjacent said table having a circular series of orifices, means for feeding caps into said orifices at one point in their path of travel, intermittently actuated liner-disk punching members above and in alignment with the orifices successively at a later point in their path of travel, paper-feed mechanism for intermittently feeding a strip of paper between said punching members, and a liner-seating plunger in axial alignment with said punching members arranged to seat liner disks in said caps.

2. In a cap-lining machine, a stationary conveyor table, an intermittently movable cap conveyor thereabove arranged to move caps successively on said table to a fixed position thereon, intermittently actuated liner-disk-cutting punching members above and in axial alignment with caps at said position, paper feed mechanism for intermittently feeding a strip of paper between said punching members, and a liner-seating plunger in axial alignment with said punching members arranged to seat liner disks in said caps.

3. In a cap-lining machine, a stationary conveyor table, an intermittently movable cap conveyor thereabove arranged to move caps successively on said table to a fixed position thereon, a punch frame arranged to reciprocate vertically, a stationary tubular die member, a tubular punch member on said frame arranged to cooperate with said die member, said punch and die members being arranged above and in axial alignment with caps at said position, paper feed mechanism for intermittently feeding a strip of paper between said punch and die members, and a liner-seating plunger coaxial with said members mounted in said punch frame and having relative vertical movement therein.

4. In a cap-lining machine, a peripherally notched turret plate and an intermittently rotated star wheel above said plate, a cap conveyor disk arranged to be rotated synchronously with said star wheel in a plane below and adjacent said turret plate and

having a circular series of orifices arranged to successively shift into registration at one position of rest with the notch in said turret plate, a conveyor table immediately below said conveyor disk, and liner-disk punching members and a liner-seating plunger in alignment with said cap conveyor orifices successively at a subsequent position of rest, said conveyor table being formed with a discharge opening in alignment with the cap conveyor orifices successively at a second subsequent position of rest.

5. In a cap-lining machine, a peripherally notched turret plate and an intermittently rotated star wheel above said plate, a cap conveyor disk arranged to be rotated synchronously with said star wheel in a plane below and adjacent said turret plate and having a circular series of orifices arranged to successively shift into registration at one position of rest with the notch in said turret plate, a conveyor table immediately below said conveyor disk, liner-disk punching members and a liner-seating plunger in alignment with said cap conveyor orifices successively at a subsequent position of rest, and a vertically reciprocating ejector member arranged in vertical alignment with said discharge opening.

6. In a machine of the class described and having an intermittently rotated star wheel for advancing the caps, feeding mechanism including a continuously moving feed belt and a vertically reciprocating stop finger arranged to successively engage the rims of caps on said belt, said finger being so arranged that by its upward movement it releases the cap on the feed belt with which it is at the time engaged and by its downward movement it engages the succeeding cap.

7. In a machine of the class described, feeding mechanism including a rotating feed table, a guide chute having a bottom member extending from without to a point over the face of said table and guide rail members extending concentrically over a portion of said table, a feed belt under and adjacent said feed table, and guide rails on opposite sides of said belt continuous with said guide rail members of said chute.

8. In a machine of the class described, feeding mechanism including a feed table arranged to rotate continuously, a continuously driven feed belt under and adjacent said feed table, said feed table being arranged to deliver caps thereon to said feed belt, guide members arranged to confine caps on said feed table and belt in a single train, and a vertically reciprocating stop finger arranged to successively arrest and release the caps adjacent the delivery end of said feed belt.

9. In a machine of the class described and having an intermittently rotated star wheel for advancing the caps, feeding mechanism

- including a feed table arranged to rotate continuously, a continuously driven feed belt under and adjacent said feed table and also extending to a point under and adjacent said
- 5 star wheel, said feed table being arranged to deliver caps thereon to said feed belt, guide members arranged to confine caps on said table and belt in a single train, and a vertically reciprocating stop finger arranged to
- 10 successively arrest and release the caps adjacent the star wheel, said belt being arranged to carry the caps successively released into the notches between the arms of said star wheel during its periods of rest.
- 15 10. In a cap-lining machine, a stationary conveyor table formed with a discharge opening, an intermittently rotated cap conveyor disk adjacent said table having a circular series of cap-receiving orifices, liner-disk
- 20 punching members in alignment with successive orifices at positions of rest of said conveyor disk and arranged to be actuated during intervals of rest of said conveyor, means for intermittently feeding a strip of paper
- 25 to said punching members, means for seating liners cut by said punching mechanism in said caps, and an ejector member in alignment with the discharge opening in said conveyor table for positively discharging the
- 30 liner caps therethrough.
11. In a cap-lining machine, a stationary conveyor table formed with a discharge opening, an intermittently rotated cap conveyor disk adjacent said table having a circular
- 35 series of cap-receiving orifices, a vertically reciprocating punch frame and a punching element thereon which is in alignment with the successive orifices at positions of rest of said conveyor disk, said frame being arranged
- 40 to be reciprocated during intervals of rest of said conveyor, means for intermittently feeding a strip of paper to said punching element, means for seating liners cut by said punching element in said caps, and an ejector element connected with said punch frame
- 45 in alignment with the discharge opening in said conveyor table for positively discharging the liner caps therethrough.
12. In a cap-lining mechanism including
- 50 a stationary conveyor table on the machine frame formed with a discharge opening and a cap conveyor formed with cap-receiving orifices arranged to move caps on said table into a position of registration with said opening and also having a vertically-reciprocating punch frame and punching members on said frame and means for seating punched liners in said caps, ejecting means for positively ejecting the lined caps through said
- 55 discharge opening in the conveyor table comprising a plunger head and connected stem, a pair of parallel arms pivoted to said stem and to said plunger frame, and a link connected to the machine frame and one of said
- parallel arms arranged to impart a multiplied movement to said plunger head.
13. In a machine of the class described and having a continuously running transfer belt and means for delivering lined caps in succession to said belt, a broad delivery belt arranged transversely of said transfer belt and having its upper reach running immediately below the upper reach of said transfer belt, means for driving said delivery belt at a slow speed, and a guide finger in the path of movement of caps on said transfer path arranged to crowd and spread the caps over the face of the delivery belt as they pass thereto.
14. In a cap-lining machine having punching mechanism for cutting cap liners, means for feeding a strip of paper to said punching mechanism including a paper reel equipped with an assembled bearing unit, said bearing unit comprising a spindle formed with an attaching portion arranged to be rigidly secured to the machine frame, and a rotative portion secured to the reel and rotatably connected in assembled relation with said spindle.
15. A structure according to claim 14 in which said spindle is formed with an attaching portion arranged to be secured to the machine frame and a bearing portion provided with bearing rings formed with separated ball races, and said reel is provided with a hub provided with corresponding internal bearing rings provided with ball races and with retaining means permitting rotation of the hub.
16. In a machine of the class described, means for feeding a pair of strips of paper comprising a pair of paper reels, a pair of idler rolls severally engaging the strips of paper running from said reels, a tension frame equipped with rolls rotatably mounted in zig-zag arrangement and engaged by the two strips of paper running together, and a pair of power-driven tensioned feed rolls frictionally engaging opposite sides of the pair of strips.
17. Mechanism according to claim 16 in which said tension frame consists of a pair of guide plates and right and left screw-threaded supporting bolts which engage said guide plates and are rotatably mounted.
18. In a cap-lining machine, an intermittently rotated star wheel, means for delivering caps into the path of said star wheel, an intermittently rotatable orificed cap conveyor, said star wheel being arranged to deliver caps vertically into the orifices of said cap conveyor, a vertically reciprocating tubular liner-cutting punch member arranged to cut liner disks, said punch member being arranged in alignment with caps in said conveyor orifices successively presented at a fixed position of rest of the conveyor, means for intermittently feeding a strip of paper to said

- punch, a liner-seating plunger arranged within said tubular punch member, and a belt conveyor having the inner portion of its upper reach extending under and adjacent said 5 rotary cap conveyor, said cap conveyor being arranged to deliver caps to said conveyor belt.
19. In a cap-lining machine, a motor, a divided clutch-connected shaft having one 10 section connected with said motor, cap-feeding mechanism operatively connected with the motor-connected section of said shaft, a main power shaft geared to the clutch-connected section of the clutch shaft, a Geneva wheel 15 crank operatively connected to said main shaft and a Geneva wheel arranged to cooperate with said crank, a rotary cap conveyor connected with said Geneva wheel, a star wheel also connected to said Geneva wheel arranging 20 to receive caps fed by said cap-feeding mechanism and transfer said caps to said cap conveyor, an eccentric on said main shaft, a reciprocating liner-cutting plunger operatively connected with said eccentric, a cam 25 carried by said main shaft, and a liner-seating plunger actuated by said cam.
20. In a cap-lining machine, a motor, a divided clutch-connected shaft having one section 30 connected with said motor, a feed belt operatively connected with the motor-connected section of said shaft, a main power shaft geared to the clutch-connected section of the clutch shaft, a Geneva wheel crank operatively connected to said main shaft and a Geneva wheel arranged to cooperate with 35 said crank, a rotary cap conveyor connected with said Geneva wheel, a star wheel also connected to said Geneva wheel arranging to receive caps fed by said feed belt, a stop finger adjacent said feed belt, operating connections intermediate said main power shaft and said 40 stop finger including a cam arranged to reciprocate said stop finger, an eccentric on said main shaft, a reciprocating liner-cutting plunger operatively connected with said eccentric, a cam carried by said main shaft, and a liner-seating plunger actuated by said cam.
21. In a cap-feeding machine, a feed belt, 45 a peripherally notched turret plate at the delivery end of said feed belt arranged to receive caps discharged therefrom, an intermittently rotated star wheel adjacent and above said turret plate, a conveyor table having a portion of its upper face arranged to underlie the notches of said star wheel, said table being 50 cut away to provide a discharge opening, an intermittently rotated cap conveyor formed with a circular series of orifices arranged in a plane between said star wheel and conveyor 55 table and arranged to receive caps through the peripheral notch in said turret plate, a tubular liner-cutting plunger in alignment with the orifices in said cap conveyor successively, means for feeding a strip of paper to 60 said plunger, and a reciprocating liner-seating plunger arranged within said tubular plunger.
22. In a machine of the class described, feeding mechanism including a vertical rotatably mounted shaft, a rotating table secured to said shaft, a horizontal rotatably mounted shaft, a pulley fixed to said shaft, a feed belt having the receiving end of its upper reach extending below and adjacent said 65 feed table and its loop at that end engaging said pulley, said vertical and horizontal shafts being equipped with intermeshing bevel pinions and the inner loop of said belt engaging a positively driven pulley.
23. In a machine of the class described, a conveyor table cut away to provide a discharge opening, an intermittently-actuated rotary cap conveyor above and adjacent said table provided with a circular series of 70 orifices, means for feeding caps vertically at a fixed point into said orifices, and aligned liner-cutting and liner-seating mechanisms for cutting and seating liners in caps at a point of rest in their travel upon said table from said feeding point to said discharge opening.
24. In a machine of the class described, a conveyor table cut away to provide a discharge opening, an intermittently actuated rotary cap conveyor above and adjacent said table provided with a circular series of 75 orifices, means for feeding caps vertically at a fixed point into said orifices, aligned liner-cutting and liner-seating mechanisms for cutting and seating liners in caps at a point of rest in their travel upon said table from said feeding point to said discharge opening, and a conveyor below said discharge opening in the conveyor table arranged to receive and 80 transfer caps discharged therethrough.
25. In a machine of the class described, a turret or star wheel mounting including a vertical shaft arranged to be positively intermittently rotated, a collar fixed to said shaft 85 having radial ribs which are wedge-shaped in cross-section, a collar loose on said shaft above said first mentioned collar and formed with complementary radial grooves, said star wheel being secured to said grooved collar, and a compression spring surrounding said shaft and stressed between said grooved collar and a nut on said shaft, whereby said star wheel will be cammed upwardly and independent rotation of said shaft permitted 90 in case of obstruction.
26. In a machine of the class described, a conveyor table, a cap conveyor arranged to successively center caps on said table at a fixed working point, a vertically-movable intermittently-actuated punch frame, a tubular punch member on said frame, a stationary tubular die member, said punch and die member being arranged in vertical alignment with 95 said working point, means for feeding paper 100

between said punch and die, a liner-seating plunger arranged to reciprocate within said tubular punch member and having a stem 5 slidably mounted in said frame, and actuating means operatively connected to said plunger stem for depressing said liner-seating plunger after the descent of the punch has severed a liner.

27. In a machine of the class described and 10 having a vertically-movable intermittently-actuated punch frame and a tubular punch member on said frame and a stationary die member, a liner-seating plunger arranged to reciprocate within said tubular punch member and having a stem slidably mounted in said frame, said stem being formed with a rack, a horizontal rock shaft journaled in said frame, a toothed segment fixed to said rock shaft arranged to mesh with said rack, 15 a gear wheel fixed to said rock shaft, a rack plate slidably mounted in said frame, an actuating rod also slidably mounted in said frame, a spring connecting said rack plate and said actuating rod, and means for reciprocating said actuating rod.

28. In a machine of the class described and 20 having a vertically-movable intermittently-actuated punch frame and a tubular punch member on said frame and a stationary die member, a liner-seating plunger arranged to reciprocate within said tubular punch member and having a stem slidably mounted in said frame, said stem being formed with a rack, a horizontal rock shaft journaled in 25 said frame, a toothed segment fixed to said rock shaft arranged to mesh with said rack, a gear wheel fixed to said rock shaft, a rack plate slidably mounted in said frame, an actuating rod also slidably mounted in said frame, a spring connecting said rack plate and said actuating rod, and a rotating cam arranged to reciprocate said actuating rod.

29. In a machine of the class described, a 30 conveyor table, a cap conveyor arranged to successively center caps on said table at a fixed working point, a vertically-movable intermittently-actuated punch frame, a tubular punch member on said frame, a stationary tubular die member, said punch and die members being arranged in vertical alignment 35 with said working point, means for feeding paper between said punch and die, a liner-seating plunger arranged to reciprocate within said tubular punch member and having a stem slidably mounted in said frame, and yielding means for depressing said liner-seating plunger after the descent of the punch has severed a liner.

30. In a machine of the class described, a 40 peripherally notched turret plate, an intermittently rotated star wheel above said plate, means for feeding caps into the path of said star wheel, and a stationary inclined spring extending above the notch in the turret plate 45 and arranged to be wiped upwardly and put

under tension by caps advancing to said notch.

31. In a cap-lining machine, a stationary conveyor table, an intermittently rotated cap conveyor adjacent said table having a circular series of cap-receiving orifices, a vertically reciprocating punch frame and a tubular punching element thereon in alignment with successive orifices of said conveyor at its positions of rest, a liner-seating plunger arranged within said tubular punching element having a stem mounted in said frame, said stem or said frame being equipped with a buffer element limiting the downward stroke of the plunger, and operating connections for reciprocating said plunger in said frame.

32. In a cap-lining machine, a stationary conveyor table, an intermittently rotated cap conveyor adjacent said table having a circular series of cap-receiving orifices, a vertically reciprocating punch frame and a tubular punching element thereon in alignment with successive orifices of said conveyor at its positions of rest, a liner-seating plunger arranged within said tubular punching element having a stem mounted in said frame, a block removably secured to said punch frame, said plunger stem being jointed and said tubular punching element and plunger 95 and the lower section of said stem being mounted in said block, whereby said block and said parts mounted therein may be removed as a unit.

In testimony whereof I have subscribed 100 my name.

EDWIN V. SWANGREN.
